UNITED STATES PATENT OFFICE.

WILTON F. JENKINS, OF RICHMOND, VIRGINIA.

SPARK PLUG.

Application filed June 23, 1920. Serial No. 391,112.

To all whom it may concern:

Be it known that I, WILTON F. JENKINS, a citizen of the United States, and a resident of Richmond, in the county of Henrico 5 and State of Virginia, have invented certain new and useful Improvements in Spark Plugs, of which the following is a specification.

My invention relates to improvements in 10 spark plugs, and it consists in the constructions, combinations and arrangements herein described and claimed.

One of the foremost objects of the invention is to provide a spark plug embodying 15 certain improvements by the use of which the central electrode is more firmly locked in position, a better electrical contact with the connected high tension wire is secured, and by means of which premature discarding 20 of the plug is obviated.

More specifically, one of the above objects resides in providing a screw head of an unusual construction, one of its functions being to scrape away foreign matter from the 25 terminal plate of the connected wire as said head is screwed down, so as to provide for itself a clean electrical contact.

A further object of the invention is to provide in combination with the above 30 screw head, lateral spindles which are employed as spark gap gages.

A further object of the invention, and one which of necessity is closely related to some of the foregoing objects, is to provide a 35 screw head for a spark plug, of such a shape that it cannot fall into the spark plug opening in the engine when the plug is removed, and thus cause later trouble.

Other objects and advantages will appear 40 in the following specification, reference being had to the accompanying drawing in which:

Figure 1 is a side elevation of the improved spark plug,

45 Figure 2 is a plan view thereof, the screw head being removed so as to show the improved lock for the central electrode,

Figure 3 is a detail perspective view of 50 the upper portion of the spark plug, showing the various members of the above lock,

Figure 4 is a plan view illustrating how 55 a place is cleaned or scraped on the terminal plate of the connected wire as the head is screwed into place,

Figure 5 is a detail perspective view of *

the screw head, the lateral gage spindles being clearly shown.

Figure 6 is an inverted plan view of the 60 spark plug, showing the improved edge electrode, and

Figure 7 is a perspective view of a part 65 of an engine, showing how it is impossible for the screw head to fall through the spark plug opening.

Considering first the general spark plug 70 construction, it is to be observed that it consists of the non-circular part 1 by means of which the threaded sleeve 2 is screwed into the usual opening 3 of the engine 4. These 75 parts are of the ordinary construction, but the porcelain core 5 is slightly modified in that it is provided with a recess 6 at the upper edge, in which the lower lip 7 of the lock washer 8 seats.

The upper lip 9 of this lock washer, 80 engages one of the faces of the jamb nut 10, and since a spring washer 11 is interposed between the washer 8 and nut 10, all loosening of the associated parts is positively prevented. These parts are fitted on the upper 85 threaded end of the central electrode 12. The spring washer 11 compensates for expansion and contraction, and the lock washer 8 prevents turning either of the nut 10 or the electrode 12.

Special attention is directed to the construction of the screw head 13. The main body thereof is made square but may be of another non-circular shape. The purpose 90 of making the body non-circular, is to insure the cleaning or scraping of a good electrical contact on the terminal plate 14 of the high tension wire 15, when the head 13 is screwed down as shown in Figure 4.

It is not uncommon that difficulties are 95 encountered in the operation of an engine simply because of a poor electrical contact at some place in the ignition circuit. It often happens that the terminal plates of the high tension wires become so coated that scraping becomes necessary. In screwing the head 13 down, the square edges cut or 100 scrape a circular seat 8 so that a good connection is provided.

The knurled head 16 enables the initial 105 turning of the screw head 13 on the threaded end of the central electrode. After the screw head is turned into place, it is firmly screwed down by using the lateral spindles 110 17 as grips or levers on which a firm hold

is gotten to accomplish the final turning of the screw head.

Gages 18 and 19 are formed on the extremities of the spindles 17. The one 18 is thinner than the one 19, the former being used to gage the spark gap when a magneto is employed in the ignition circuit, as indicated by the initial letter "M," the latter being used to gage the spark gap when a battery is employed in the ignition circuit, as indicated by the initial letter "B."

Both gage points are chisel-shaped as clearly shown in Figure 4, but the gage 19 is additionally sharpened at 20 to provide 15 a scraping edge which is useful in making a clean contact place on such part whereon it may be found expedient to use it.

Attention is now directed to the construction of the spark gap. The central electrode 20 12 is of a usual construction, but the edge electrode 21 is made of a substantial V-shape so as to produce two legs 22 which are respectively grounded in the body of the spark plug at separate places. Obviously it will 25 be with considerable difficulty that the electrode 21 could be dislodged, and it is contemplated that this form of electrode will survive any ordinary and even moderately rough use of spark plug.

30 In using the gage points 18 and 19, one or the other is to be inserted into the gap G which is to be adjusted by bending the electrode 12 in the proper direction until the space is fixed according to that one of the 35 points used as a gage. The spark gap is slightly greater for battery current than it is when current from a magneto is used.

Figure 7 illustrates how impossible it is 40 for the screw head 13 to fall into the spark plug opening 3 of the engine 4. Naturally this is by reason of the fact that the screw head is of considerable size, and at any event, larger than the hole for the sleeve 2. In constructions of well known types of 45 spark plugs, relatively small binding nuts are used to fasten the high tension wires in place.

It often happens that in making adjustments about his engine, an operator will lay 50 this binding nut on the head of the engine, and it moving about brush it into the open hole 3. Obviously trouble will commence when attempting to run the engine with a metallic piece in the compression or working 55 chamber, which ought to be clear. The special construction of the screw head, while not intended primarily to avoid the loss of the usual binding nut, does prevent any damage which might occur by the falling of such nut into the engine, because of its 60 large size as indicated above.

I claim:—

1. A binding screw for spark plugs, etc. with non-circular portions for scraping a clean contact seat on a terminal plate, when 65 screwing it into place.

2. A spark plug, including a central electrode and the terminal plate of a high tension wire fitted thereon, and a screw head arranged to produce a clean contact on said 70 plate as it is screwed thereagainst on said electrode.

3. A spark plug, including a screw head with an upper knob for initially twirling the head on the threaded end of a central 75 electrode, and a non-circular base providing cutting edges for producing a clean contact seat when the head is screwed into engagement with a terminal plate.

4. A spark plug, including a screw head 80 with an upper knob for initially twirling the head on the threaded end of a central electrode, a non-circular base providing cutting edges for producing a clean contact seat when the head is screwed into engagement 85 with a terminal plate, and means on the screw head enabling obtaining a leverage in finally turning it, to avoid the use of a wrench or the like.

5. A spark plug, including a screw head 90 with an upper knob for initially twirling the head on the threaded end of a central electrode, a non-circular base providing cutting edges for producing a clean contact seat when the head is screwed into engagement 95 with a terminal plate, and lateral spindles on the screw head enabling obtaining a leverage in finally turning it, said spindles including extremities formed into spark gap 100 gages.

6. A spark plug, including an insulating bushing with a recess, and a lock washer with a lip seated in the recess.

7. A spark plug, including an insulating bushing with a recess, and a central electrode; a lock washer on the electrode with one lip seated in the recess, a lock nut on the electrode engaged by another lip of said washer to prevent turning, and a spring washer between the lock nut and lock washer 105 to compensate for expansion and contraction.

8. A spark plug, including an insulating bushing with a recess, and a central electrode; a lock washer on the electrode with one lip seated in the recess, a lock nut on the electrode engaged by another lip of said washer to prevent turning, a spring washer between the lock nut and lock washer to 115 compensate for expansion and contraction, and a head screwed on the electrode to bind the terminal plate of a wire against the lock nut.

WILTON F. JENKINS.
